UNITED STATES PATENT OFFICE.

EMORY GLENN SIMPSON, OF DETROIT, MICHIGAN, ASSIGNOR TO FISHER BODY CORPORATION, OF DETROIT, MICHIGAN, A CORPORATION OF NEW YORK.

WINDOW REGULATOR.

Application filed March 28, 1924. Serial No. 702,753.

This invention relates to window regulators and has for its object a window regulator which is arranged to lift a relatively wide window by force applied at two widely spaced points. It is the object of the invention to lift a relatively wide heavy window a relatively small distance.

The primary purpose of the window regulator is to raise and lower a windshield panel.

In the drawings:

Fig. 1 is a fragmentary inside elevation of a closed body above the windshield.

Fig. 2 is a section taken on the line 2—2 of Fig. 1.

Fig. 3 is a fragmentary view of the top of the windshield panel.

Fig. 4 is a section taken on the line 4—4 of Fig. 3.

Fig. 5 is an enlarged section on the line 5—5 of Fig. 1.

Fig. 6 is a section on the line 6—6 of Fig. 5.

Fig. 7 is a perspective of the window guide bracket.

Fig. 8 is a detail of the clip for anchoring the cable to the pulley wheel.

Fig. 9 is a section on the line 9—9 of Fig. 8.

Fig. 10 is an enlarged section on the line 10—10 of Fig. 1.

Fig. 11 is a section on the line 11—11 of Fig. 10.

a designates a windshield panel arranged to raise and lower about four or more inches into the header *b*. This header is provided with an outside board *c* and a removable inside header board *d*. The removable inside header board has a fixture *e* secured thereto by screws. A piece of plush *10* is secured to the outside header board; a second piece of plush *j* is looped over the outside face of the fixture and tacked to the wooden strip *f*. The bracket and the plush serve to prevent the whipping of the wide windshield panel and hold it firmly so it will not rattle, for the windshield panel has less thickness than the width of the header chamber. The top of the windshield panel is provided with a channel *k* and riveted or welded to the top of this channel are a pair of loop bars *m* in which the lifter pins *n* are arranged to travel.

The regulator itself is mounted on the removable header board *d*. This header

board has a channel strip *o* secured by screws to the top of the header board. This forms a groove adapted to be fitted over the tongue *p* which is part of the top header board *q*. The trimming *r* drapes down over the tongue; hence, by simply taking out the screws *s* which secure the removable header board *d* to brackets *t*, the header board may be removed as a unit taking with it the regulator which is the subject matter of this invention. This particular header and body construction, which enables the regulator to be removed as a unit is not claimed in this application but is made the subject of a separate application, Serial No. 701,908 on body construction, for obviously, the regulator that can be mounted on this unit header board may vary within wide limits.

The regulator comprises a pair of supporting plates *u* and *v* connected by a horizontal spacer bar *w*. The supporting plate *u* journals studs carrying the driving pinion *v* and driven gear *z*. The driving pinion is driven from the crank handle *1* through the clutch *2*, contained within the clutch case designated by this character. The clutch may vary within wide limits so it is not shown in detail; suffice it to say that any suitable clutch may be used; the one I prefer to use is the one shown in the Schmidt, Karstens, Simpson Patent No. 1,343,410. In a clutch of this kind, the turning effort originating in the handle is freely communicated to the driving pinion to rotate the same. However, effort originating in the window and communicated through the driven gear to the driving pinion causes the clutch parts to lock and prevent either the panel raising or lowering. On the back of the supporting plate is a pulley wheel *3* over which runs the wire cable *4*. The cable is anchored to the pulley wheel by the removable clip *11* which fits into the notch *12*. The cable crosses at the center of the regulator as shown in Fig. 1 and runs over and is in the same manner anchored to the pulley wheel *13*, which is rotatably supported on the other supporting plate *v*. Each of these pulley wheels is in effect a crank arm for each carries the lifting pin *n* and thereby forms a lifting member. By turning the crank handle the clutch parts are caused to engage with and turn the driving pinion *v*. This in turn drives the gear *z* which is coupled up with the pulley *3*. The pulley

through the crossed cable drives the other pulley wheel in a reverse direction precisely the same distance because the two pulleys and cable are anchored together. This is quite important as the side thrusts of each crank arm is thereby neutralized and the result is that the window panel is lifted straight up the same way it would be with a thrust directly on the center, in fact, there is even less tendency for the window to cock in the window guides.

With this arrangement the window regulator crank handle can be located at one side or the other of the car. This makes it very convenient for the driver of the car as it can be almost directly above the steering post. It will also be noticed that the crossed cable passes through the center of the fixture *e* so that this prevents the cable from lashing back and forth in the header well.

What I claim is:

1. In a windshield regulator, the combination of a pair of plates and a spacer bar connecting the plates, lifting members, one supported on each plate and each arranged for connection at the top and to one side of center of the shield, driving connections between the two lifting members, and means for driving the same.
2. In a windshield regulator, the combination of a regulator frame, a rotary lifting member journaled on each end and when in place being in a plane parallel with the windshield but said members remotely spaced, said members having each connections adapted to connect with the windshield to raise and lower the same from spaced points, operating connections between the said lifting members for driving the same in unison, and means for driving the said parts.
3. In a windshield regulator, the combination of a frame arranged when installed to have its length horizontally directed and to be in a plane substantially parallel with the windshield panel, a pair of lifting members mounted operatively upon said frame at opposite ends considerably spaced from each other and lying in planes substantially parallel with the frame, driving connections between the said lifting members to cause the same to operate together, connections secured to the lifting members for connecting each lifting member with the top of the windshield panel at widely spaced points, and means by which the lifting members may be caused to operate.
4. In a window regulator, the combination with a panel arranged to slide vertically

and a relatively long and narrow regulator mechanism arranged to be installed in a header pocket and provided with operating connections with the panel which slidably engage the top of the panel at spaced points and are arranged to both forcibly lift the panel and force the same down.

5. In a window regulator, the combination of two widely horizontally spaced rotating members provided each with a crank pin for raising and lowering a window panel, a crossed cable connecting the rotating members, and means for rotating one of the members.

6. In a window regulator, the combination of a pair of widely spaced rotating members arranged for location in a narrow header pocket, means on each rotating member for engaging the upper edge of the window panel to raise and lower the same, operating connections between the two rotating members, and means by which one of the rotating members may be rotated.

7. In a window regulator, the combination of two widely horizontally spaced rotating members, each having a connection with one of the edges of a window panel for raising and lowering the same, a crossed linear member anchored to both rotating members and operatively connecting the two rotating members and causing them to rotate in opposite directions, and means by which one of the rotating members may be turned.

8. In a windshield regulator, the combination of a flat frame arranged to be fitted into the header pocket between the wall of the header and the path of travel of the shield panel, lifting means having its greater dimension substantially in the plane of the frame and being of comparatively little thickness to lie between said wall and the path of travel of the panel, and means arranged to pass through the said header wall for operating the lifting means.

9. In a windshield regulator, the combination of a frame, a lifting member located on one end of the frame and arranged for connection with the top of a windshield panel, a second lifting member on the other end of the frame and arranged for connection with the top of the said panel, and means for simultaneously operating said lifting members, the said frame and parts thereon arranged for location wholly within the pocket of the header of the windshield.

In testimony whereof I affix my signature.

EMORY GLENN SIMPSON.

CERTIFICATE OF CORRECTION.

Patent No. 1,643,320.

Granted September 27, 1927, to

EMORY GLENN SIMPSON.

It is hereby certified that the above numbered patent was erroneously issued to "Fisher Body Corporation, of Detroit, Michigan, a corporation of New York" whereas said patent should have been issued to "General Motors Corporation, of Detroit, Michigan, a corporation of Delaware," said corporation being assignee by mesne assignments of the entire interest in said invention, as shown by the records of assignments in this office; and that the said Letters Patent should be read with this correction therein that the same may conform to the record of the case in the Patent Office.

Signed and sealed this 8th day of November, A. D. 1927.

Seal.

**M. J. Moore,
Acting Commissioner of Patents.**
